UNITED STATES PATENT OFFICE.

THOMAS F. MATTHEWS, OF PHILADELPHIA, PENNSYLVANIA.

BOOK-MARKER.

1,210,964.

Specification of Letters Patent. Patented Jan. 2, 1917.

Application filed February 23, 1916. Serial No. 79,842.

To all whom it may concern:

Be it known that I, THOMAS F. MATTHEWS, a citizen of the United States, residing in the city and county of Philadelphia, 5 State of Pennsylvania, have invented a new and useful Book-Marker, of which the following is a specification.

My invention consists of a book marker which is composed of a piece or plate of 10 suitable material, and a hanger therefor, the latter being adapted to be attached to a proper part of the back or leaves of a book, and the former to be placed between said leaves, and so retain its position there 15 whether the book is open or closed, it being simple, durable, and inexpensive in its nature.

The invention is satisfactorily illustrated in the accompanying drawing, but the important instrumentalities thereof may be 20 varied, as long as they are included in the scope of the claims.

Figure 1 represents a perspective view of a book marker embodying my invention. 25 Figs. 2 and 3 represent perspective views of other embodiments thereof.

Similar numerals of reference indicate corresponding parts in the figures.

Referring to the drawings, 1 designates a 30 card which is formed of paper or paper material, sheet metal, celluloid, etc., and has thereon an angular member 2 integral therewith and composed of the horizontal limb 3, which projects laterally from a side of 35 said card, more particularly at the upper corner thereof and the vertical limb 4 which depends from the outer terminal of said limb 3, comprising together a hanger of the form of a hook for suspending the card between the leaves of a book for service of the 40 order of a book-marker. As a well defined space exists between the side of the card and said vertical limb, and the latter is in the same vertical plane as the card, the hanger 45 may be hooked on the edges of the leaves of a book or between the back bone of the book and the adjacent portions of the signatures of the leaves, or upon said back bone limited by the horizontal limb 3 as a 50 stop, while the card rests flat between the leaves without materially affecting the closing of the book, said card being adapted

also for having names of the donor of a book written or printed thereon, for addresses, advertisements, and other purposes. 55 The hanger in each case adapts the card to remain reliably connected with a book without liability of dropping or shifting therefrom. The marker may be readily removed and applied to another book and so render 60 continual service.

In Fig. 2, I show an angular hook or hanger formed by a piece of wire or other material bent into angular form, the horizontal limb 5 of which is secured firmly to 65 the card by being reeved thereinto, and further engaged by the clip 6 which is fitted and clamped over said limb and connected with the adjacent portion of the card. The hanger in this instance is applicable to a 70 book, the same as in Fig. 1, as in the previous case.

In Fig. 3, I show an angular hanger whose horizontal limb 7 is formed integral with a clip 8 of the form of an eyelet, the 75 latter being adapted to be clenched to the card, and so firmly connect the hanger with the latter.

Having thus described my invention what I claim as new and desire to secure by Letters Patent, is:—

1. A book marker composed of a card, an angular hanger thereon substantially in the same vertical plane as that of said card, said hanger being composed of horizontal 85 and vertical limbs, the horizontal limb of said hanger being on said card, and a clip which is secured to said card and adapted to clamp said horizontal limb thereto.

2. A book marker composed of a card, 90 and an angular hanger thereon provided with horizontal and vertical limbs, the latter being in substantially the same vertical plane as that of said card, the horizontal limb of the latter being imposed on said card, and a clip fixed to said card adapted to clamp said horizontal limb to the card, and the other limb depending from the first named limb forming together a hook which is set out from the side edge of said card. 95

3. A book marker composed of a card, and an angular hanger thereon on a side thereof, said hanger being formed of horizontal and vertical limbs, the horizontal

limb of said hanger extending outwardly from the upper corner portion of said card, and the vertical limb depending from the outer end of said horizontal limb and being set out from the side edge of said card, said horizontal limb forming a stop for the descent of the card, said horizontal and verti-

cal limbs being substantially in the same vertical plane as that of said card.

THOMAS F. MATTHEWS.
